COWLING FOR COIN CONTROL MECHANISM FOR VENDING MACHINES

Carl C. Bernitz, Kansas City, Mo.

Application June 7, 1948, Serial No. 146,798

Term of patent 14 years

(Cl. D52—3)

To all whom it may concern:

Be it known that I, Carl C. Bernitz, a citizen of the United States, residing at Kansas City, in the county of Jackson and State of Missouri, have invented a new, original, and ornamental Design for a Cowling for Coin Control Mechanism For Vending Machines, of which the following is a specification, reference being had to the accompanying drawing forming a part thereof.

Figure 1 is a plan view of a cowling for coin control mechanism for vending machines showing my new design.

Fig. 2 is a right side view of the cowling.

Fig. 3 is a front view of the cowling.

Fig. 4 is a left side view of the cowling; and

Fig. 5 is a rear view of the cowling.

I claim:

The ornamental design for a cowling for coin control mechanism for vending machines, as shown.

CARL C. BERNITZ.
